UNITED STATES PATENT OFFICE.

THOMAS DEDIO, OF DNIPRO, ALBERTA, CANADA.

SHIP'S TABLE.

1,104,251.

Specification of Letters Patent.

Patented July 21, 1914.

Application filed March 16, 1914. Serial No. 825,027.

To all whom it may concern:

Be it known that I, THOMAS DEDIO, a subject of the Emperor of Austria-Hungary, residing at Dnipro, Alberta, Canada, have 5 invented certain new and useful Improvements in Ships' Tables, of which the following is a specification.

This invention relates to certain new and useful improvements in Ships' Tables.

10 An object of the invention is to provide a stabilizing table for ships that will always occupy a horizontal position thereby preventing articles placed thereon from upsetting or falling off the table.

15 With the above and other objects in view that will appear as the nature of the invention is better understood, the same consists in the novel construction, combination, and arrangement of parts to be hereinafter more 20 fully described and then claimed, reference being had to the accompanying drawing by like characters throughout the several views, and wherein:

25 Figure 1 is a perspective view of a ship's table embodying my invention. Fig. 2 is a cross sectional view of the same, and, Fig. 3 is a top plan view of the stabilizing weight detached.

30 Referring more specifically to the drawing accompanying this application which illustrates a preferred embodiment of my invention, the reference numeral 10 designates the legs of the table, the legs preferably being formed of sheet metal and bent 35 at their lower ends to provide feet 11 by which the same may be secured to a floor or other support. The legs 10 are inclined inwardly and at their upper ends receive a head block 12 that is suitably secured 40 thereto.

The table top 13 is preferably oblong in shape and is mounted upon the head block 12 in a manner so as to always occupy a horizontal position. Secured to the under- 45 side of the table top 13 are transversely ar- ranged plates 14 and 15, the said plates being bent downwardly at right angles at their ends to provide ears 16 and 17 that are dis- posed adjacent the edge of the table top 13.

50 An eye 18 is secured to the under face of the table top in the center thereof and receives an eye bolt 19 that extends into the head block as at 20 to constitute the support for the table.

55 Secured to the under side of the head block 12 is an eye bolt 21 and suspended

from the eye bolt 21 is a freely-movable rod 22, headed at its lower end as at 23 to provide a support for the stabilizing weight 24. A collar 25 of configuration similar to the weight 24, surrounds the weight and is provided at its lower end with a right-angularly bent flange 26. The flange 26 and ears 16 and 17 are apertured to receive the ends of connecting links between the table 60 top 13 and the weight 24. These connecting links comprise side links 27 loosely connected at their upper ends to the ears 16 and at their lower ends to the flange 26. The end links 28 are loosely connected at their upper 65 ends to the ears 17 and to provide a clearance for the legs 10 are joined together for a portion of their lengths as at 29, the said links separating at a point adjacent their lower ends to be secured to the flange 26. 70

The eye bolt connection 18 and 19 between the table top 13 and the head block 12 is a universal joint and the weight being connected to the table top by the links 27 and 28, the said table top is caused to always 80 assume a horizontal position, regardless of the rocking of the ship or the roughness of the sea.

While I have shown and described the preferred embodiment of my invention, I 85 do not wish to confine myself thereto, as various forms, modifications, and arrangement of parts as shown may be had without departing from the spirit and scope of the invention as claimed.

I claim:

1. A self-leveling table, comprising a table-top, transverse plates secured to the under side of the table-top and provided with depending ears at their ends, support- 95 ing legs secured at their upper ends to a head-block, an eye-bolt depending centrally from said top, a second eye-bolt extending centrally through the head block and connecting with the eye-bolt of the table, an eye- 100 bolt depending centrally from the under side of said head block, a rod loosely connected to said last-named eye-bolt, a weight suspended upon the lower end of said rod, and link connections between said weight and said de- 105 pending ears.

2. A self-leveling table, comprising a table-top, transverse plates having depend- 110 ing perforated ears at their ends secured to the under side of the table-top, table-sup- porting legs having their lower ends adapted to be secured to a floor, a head-block to

2
which the upper ends of the legs are secured, eye-bolt connections between said head-block and the table-top, a rod loosely-suspended centrally from said head block, a weight secured to the lower end of said rod, a collar surrounding said weight and formed with an annular flange, and diverging links connected at their lower ends to said flange and

hooked into the perforations of said ears at their upper ends.

In testimony whereof I affix my signature in presence of two witnesses.

THOMAS DEDIO.
